UNITED STATES PATENT OFFICE.

WALTER M. LONG AND LOU S. LEMERE, OF SEATTLE, WASHINGTON.

DESIGN FOR AN AUTOMOBILE NAME PLATE.

Application filed October 24, 1922. Serial No. 4,070. Term of patent 7 years.

To all whom it may concern:

Be it known that we, WALTER M. LONG and LOU S. LEMERE, citizens of the United States, residing at Seattle, in the county of King and State of Washington, have invented a new, original, and ornamental Design for an Automobile Name Plate, of which the following is a specification, reference being had to the accompanying drawing, forming part thereof.

We claim:

The ornamental design for an automobile name plate as shown.

WALTER M. LONG.
LOU S. LEMERE.
